(57) **CLAIM**

We claim the ornamental design for an illuminated tractor, as shown and described.

DESCRIPTION

FIG. 1 is a left side front perspective view of an illuminated tractor;

FIG. 2 is a right side front perspective view thereof;

FIG. 3 is a right side rear perspective view thereof;

FIG. 4 is a left side rear perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof;

FIG. 10 is a bottom view thereof;

FIG. 11 is a top sectional view thereof taken along line 11-11 of FIG. 5;

FIG. 12 is a left side front perspective view thereof with the illuminated tractor in an illuminated state;

FIG. 13 is a right side front perspective view thereof with the illuminated tractor in an illuminated state;

FIG. 14 is a right side rear perspective view thereof with the illuminated tractor in an illuminated state;

FIG. 15 is a left side rear perspective view thereof with the illuminated tractor in an illuminated state;

FIG. 16 is a right side view thereof with the illuminated tractor in an illuminated state; and,

FIG. 17 is a left side view thereof with the illuminated tractor in an illuminated state.

The ornamental design which is claimed is shown in solid lines in the drawings. The dashed broken lines in the drawings illustrate environmental structure and form no part of the claimed design. The stippling in FIGS. 12-17 is shown to illustrate contrasting surfaces, a contrast between surfaces that are illuminated through the emission of light and surfaces not illuminated. The radiating broken lines shown

(Continued)

in FIGS. 12-17 represent visible light being emitted by the illuminated surfaces (shown with stippling) in the illuminated state.
